UNITED STATES PATENT OFFICE.

HIERONYMUS MUELLER AND JOHN GROSS, OF DECATUR, ILLINOIS.

WATER-PRESSURE REGULATOR.

SPECIFICATION forming part of Letters Patent No. 251,726, dated January 3, 1882.

Application filed July 9, 1881. (No model.)

To all whom it may concern:

Be it known that we, HIERONYMUS MUELLER and JOHN GROSS, citizens of the United States, and residing at Decatur, in the county 5 of Macon and State of Illinois, have invented a new and useful Improvement in Water-Pressure Regulators, of which the following is a specification.

Our invention relates to a new and useful 10 improvement in water-regulators; and the object of our improvement is to so construct a regulator that an equal amount of pressure is maintained in the supply-pipes of a building irrespective of the pressure of water in the 15 main; and it consists in the construction and arrangement of valves, their containing case or shell, and an adjusting device, as hereininafter fully described. These objects are attained by the device illustrated in the accompanying 20 drawing, in which the figure is a transverse vertical section of a water-regulator embodying our invention.

Individual parts are designated by letters.

A is the case or shell, and B the dome. C 25 is the inlet-orifice, and C' the discharge-orifice. D is the plunger or valve-rod, onto which all 30 of valves, washers, and diaphragm are attached and arranged in order as follows, viz: The valve H is passed onto the rod against the 35 flange a of the rod, followed by the metallic sleeve b, which has a recess cut into the end to receive the lower half of the valve H and secure it from lateral displacement, the opposite end of which is convex in form to fit within 40 the concavity of the cup shaped leather disk c, which is in turn backed up by the metallic washer d. The flat rubber disk e is then placed on the rod and the whole secured thereto by the flanged nut f.

45 The upper end of the valve-rod is provided with the flange a', which supports the leather cup-shaped diaphragm G, which is secured thereto as follows: First, the metallic washer g is placed on the rod, followed by the leather cup-shaped diaphragm G, which is followed by the cup-shaped metallic washer g', that fits the convexity of the leather diaphragm and acts as a support to prevent bursting or collapse of the diaphragm. The nut h serves to secure the 50 diaphragm and washers to the rod.

The valve-chamber A' forms a part of the

case or shell, having an opening for the passage of water at i. In said opening is formed the valve-seat for the valve H, which controls the emission of water into the discharge-pipes. The 55 course of the water is indicated by the arrows.

The dome B is screwed onto the case or shell above the diaphragm, and is provided with the adjusting-screw j and a spiral spring, I, one end of which rests on the top of the valve- 60 stem, and its opposite end bears against the adjusting-screw, (the washer j' being inserted between them,) by which a given and equal pressure is maintained in the supply-pipes.

Its operation is as follows: A water-gage 65 being attached to the discharge pipe C' at any point desired—for example, say we have one hundred pounds pressure of water on the main or inlet pipe C, and only require, say, fifty pounds pressure on the discharge-pipe of the building—and the water being admitted to the regulator through the inlet-pipe C, the adjusting-screw j is screwed down, increasing the tension of the spring until it forces the valve H open against the pressure in the main. The water 70 thus admitted, after filling the pipes of the building and having attained the required pressure therein, backs up against the diaphragm G, overpowering the spring and causing the valve to close until the pressure on the discharge-pipe is relieved. Then the spring will again 75 open the valve, admitting more water from the main and by this means maintaining an equal pressure on the outlet-pipes.

There is an opening at the bottom of the 80 shell or casing, and also in the valve-chamber, through which the plunger or valve-rod is inserted when assembling the parts. The former is closed by a screw-plug, K, which is concealed to admit of the downward movement of the 85 valve-rod. The latter is closed by the cup-shaped leather disk c, which fits water-tight within the chamber, and the flat rubber disk e.

The chamber formed in the lower part of the case below the valve-rod has communication 90 to the outlet portion of the case only through a series of perforations in the inner wall, A', at e', the object of this being to allow the lower chamber to fill with water under the same pressure as that in the outlet portion of the case, 95 and allow it to act upon the lower end of the plunger for the purpose of preventing what is 100

known to the art as "water-hammer," or a continual jarring of the valve in its seat caused by the unequal pressure of the water in the main or inlet pipe, to which it is subjected at

5 all times.

It will be seen by reference to the drawing that the diaphragm G does not change its form in operating, but slides within the vertical projection of the case or shell and allows no water 10 to pass into the dome.

In order to distinguish the difference between our improved regulator and those heretofore invented to accomplish a similar result, we would refer to the particular formation of the 15 regulating-diaphragm G, which is cup shaped, having high side walls, which afford a bearing against the sides of the cylinder within which it is placed, and having no friction against the sides of the cylinder except when under 20 pressure, the bearing-surface of the cup against the sides of the cylinder being equal to the area of its flat surface, upon which the water has direct action to force it up and close the valve, as hereinbefore described.

25 It is obvious that there is another special advantage in having these side walls of the dia-

phragm high, as shown—viz., that it affords a large bearing-surface on its interior for the water to act upon to force the side walls out against the cylinder, thus making it practically 30 water-tight.

The dome within which the spring is contained may be perforated at any point desired to prevent the air from being compressed within the dome and thus interfering with the perfect action of the plunger. 35

Having thus described our invention, what we claim, and desire to secure by Letters Patent, is—

The combination of the case A, provided with 40 a removable bottom plug, K, the cup-shaped diaphragm G, adapted to slide within said case, valve-stem D, and conical valve H, with sleeve b, dished valve c, and the rubber disk e, adapted to rest against the bottom edge of the valve-chamber A', substantially as and for the purposes described.

HIERONYMUS MUELLER.
JOHN GROSS.
